UNITED STATES PATENT OFFICE.

CLAYTON E. FREDERICKSON, OF SAN FRANCISCO, CALIFORNIA, ASSIGNOR OF ONE-HALF TO W. H. STENGER, OF SAN FRANCISCO, CALIFORNIA.

PIPE-ANCHOR.

1,074,427.

Specification of Letters Patent. Patented Sept. 30, 1913.

Application filed January 24, 1912. Serial No. 673,001.

To all whom it may concern:

Be it known that I, CLAYTON E. FREDERICKSON, residing at San Francisco, in the county of San Francisco and State of California, have invented certain new and useful Improvements in Pipe-Anchors, of which the following is a specification.

In pumping oil wells, the present practice usually is to employ a string of two inch pipe to convey the oil up out of the well. This pipe is let down into the well tube or casing and owing to its great length, it has a tendency to elongate or stretch and it not infrequently becomes broken. In order to prevent this breaking and undue elongation, and in order to render the action of the pump more efficient, I have provided a mechanism for effecting an anchoring or fixing of the pipe in the well casing and thereby support its weight from below instead of above.

Generally, the invention embodies a slidably supported gripper device that coöperates with a spreader cone on the pipe and with a setting mechanism, whereby, when the pipe is in the well, by lifting upon the same and then lowering it again, the grippers may be set and spread to hold the pipe in the well casing.

More specifically the invention embodies those novel features of construction, combination, and arrangement of parts, all of which will be first fully described, then be specifically pointed out in the appended claims, reference being had to the accompanying drawing, in which:

Figure 1 is a vertical longitudinal section showing the invention with the parts in the position they assume while the pipe is being lowered into the well and taken substantially on the line 1—1 of Fig. 4. Fig. 2 is a view similar to Fig. 1 but taken on the line 2—2 of Fig. 4, and showing the position of the parts when the setting mechanism is in co-operative position with the gripping mechanism, and just prior to the lowering of the pipe to wedge out the grippers. Fig. 3 is a view similar to Fig. 2, showing the position of the parts after the pipe has been lowered to spread the grippers. Fig. 4 is a cross section on the line 4—4 of Fig. 2.

In the drawing, like numerals and letters of reference indicate like parts in all the figures.

1 represents the well casing, which may

be of the ordinary type, and 2, represents the string of pipe employed in the well. The pipe 2 is made in sections 2, 3, and 4, the sections 2 and 3 being united by a coniform collar 6 which acts as a spreader for spreading the grippers 9. The sections 3 and 4 of the pipe are joined by an ordinary collar 5, which acts as an abutment for the ring 7, that carries the resilient arms 8, on the upper ends of which, the grippers 9 are secured. 60 The grippers 9 have their inner faces beveled off, as at 10, and have their outer faces serrated, as at 11, whereby, the grippers 9 may coöperate with the spreader 6, and with the well casing 1, as indicated in Fig. 3, to hold the pipe 2 fixed or rigidly supported in the well casing. Beneath the collar 5, on the pipe section 4, is slidably mounted a pair of collars 12 and 13, which are united by bow springs 14, which act as retarders or friction members to engage the well casing 1. The collars 12 and 13, and springs 14 form a part of what I term, the setting mechanism, the remainder of which is constituted by the spring arms 15, the upper or free ends of which have hook or shouldered portions 16, that engage the collar 7 at times to retard or hold the same, while the spreader 6 is being forced down to spread the grippers 9. In order to prevent the setting mechanism from leaving the pipe, a collar 17 may be employed as indicated in Fig. 3.

In the practical use of my invention, the parts are assembled in the position shown in Fig. 1 with the arms 15 resting between the arms 8, with the collars 7 and 12 adjacent to the union collar 5. The pipe line or string 2 with the invention applied is lowered into the well as far as may be desired, after which the pipe is pulled up slightly until the collar 7 passes the shoulders 16, and rests in the same, after which, the string of pipe is again lowered. On again lowering the pipe, it will be noted, the bow springs 14, by reason of friction, of their engagement with the well casing, will hold the collars 12 and 13 from movement with relation to the well casing, and consequently the arms 15 hold the collars 7 from movement while the spreaders 6 are lowered between the grippers 9 and spread them into engagement with the well casing 1, as indicated in Fig. 3 of the drawings.

In order to remove the string of pipe from

the well, it is only necessary to pull up on the same when the spreader 6 will leave the grippers 9 which will, thereupon return to the position shown in Figs. 1 and 2, and 5 the entire mechanism may be entirely withdrawn from the well casing or tube.

From the foregoing description taken in connection with the accompanying drawings, 10 it is believed the complete construction, operation, and advantages will be apparent to those skilled in the art to which the application appertains.

What I claim is:—

1. The combination with the pipe line or 15 string, of a gripping mechanism slidably mounted thereon, and including a collar, grippers resiliently mounted on said collar, a gripper spreader mounted on said pipe, and a setting mechanism carried by said 20 pipe and coöperative with the well casing, for holding the gripping mechanism in position, while said spreader is brought into action to spread the grippers into engagement with the well casing said setting mechanism being separate and distinct from and 25 having no positive connection with said gripper spreader, said grippers, and the collar on which said grippers are mounted.

2. In combination with the pipe line or 30 string, of a gripper carrying collar slidably mounted thereon, grippers carried by said collar, a gripper spreader fixedly located on the pipe line, a well engaging setting device slidably mounted on the pipe line, and means carried 35 by said device and coöperative with said collar to hold said gripping mechanism from movement when said pipe is lowered, to cause said gripper spreader to act said setting mechanism being separate and distinct from 40 and having no positive connection with said gripper spreader, said grippers, and the collar on which said grippers are mounted.

3. In combination with the pipe line of a stop fixed thereon, a gripper carrying member 45 slidably mounted on said pipe above said stop, a spreader relatively fixedly located on said pipe above said stop and coöperative with the grippers of said gripper carrying member, a setting mechanism

mounted on said pipe below said stop, and 50 including members for engaging said gripper carrying mechanism at times to hold said gripper carrying mechanism immovable with relation to the well casing while said spreader is acting said setting mechanism being separate and distinct from and having no positive connection with said gripper spreader, said grippers, and the collar on which said grippers are mounted.

4. The device of the class described a pipe 60 line, a stop relatively fixedly located on said pipe line, a spreader relatively fixedly located on said pipe line, a gripping mechanism slidably mounted on said pipe line, between said stop and said spreader, and including gripping elements coöperative with said spreader, a setting mechanism slidably mounted on said pipe line beyond said stop, said setting mechanism including a slidably mounted well casing engaging device, and 65 resilient arms having portions for engaging said gripper carrying mechanism at times to hold the same stationary, while said spreader is acting said setting mechanism being separate and distinct from and having no positive connection with said gripper spreader, said grippers, and the collar on which said grippers are mounted.

5. In a device of the class described, a 70 pipe line, a stop fixed on the pipe line, a gripping mechanism slidably mounted on the pipe line above said stop and including a slidable collar, a gripper spreader mounted on the pipe line to coöperate with the gripping mechanism to force it into its 75 gripping position, and a setting mechanism separate and distinct from said gripping mechanism, said setting mechanism including well engaging devices, and resilient arms coöperative with the gripping mechanism 80 collar to hold the gripping mechanism immovable while said spreader is in operation, substantially as shown and described.

CLAYTON E. FREDERICKSON.
